UNITED STATES PATENT OFFICE.

WILLARD HARRISON ELLIS, OF CHEYENNE, WYOMING.

GUARD-RAIL FOR RAILWAY-BRIDGES.

1,366,641.

Specification of Letters Patent. Patented Jan. 25, 1921.

Application filed August 6, 1920. Serial No. 401,757.

To all whom it may concern:

Be it known that I, WILLARD HARRISON ELLIS, a citizen of the United States, and a resident of Cheyenne, in the county of Laramee and State of Wyoming, have invented certain new and useful Improvements in Guard-Rails for Railway-Bridges, of which the following is a specification.

My invention relates to railway bridges and more particularly to guard rails therefor, a purpose of my invention being the provision of a simple and inexpensive guard rail which effectively secures the deck ties in proper spaced relation on the girders, and which permits removal and replacing thereof when substituting new ties without detriment to the guard rails.

I will describe one form of guard rail embodying my invention and will then point out the novel features thereof in claims.

In the accompanying drawings:

Figure 1 is a fragmentary view showing in top plan one form of railway bridge having thereto one form of guard rail embodying my invention.

Fig. 2 is a vertical sectional view taken on the line 2—2 of Fig. 1.

Fig. 3 is a fragmentary detail view showing in perspective one of the guard rails shown in Fig. 1.

Referring specifically to the drawings, in which similar reference characters refer to similar parts, G designates a pair of girders, each of which, as shown in Fig. 2, is in the form of an I-beam. Supported upon and extending transversely of the girders G are wooden ties T of the ordinary form, and supported upon the latter are the rails R of a railway track. The guard rails forming the subject matter of my invention are designated at D, such rails being arranged transversely of and adjacent the opposite ends of the ties T. As illustrated to advantage in Fig. 3, each guard rail is formed from an angle bar of suitable metal, the lower web portion of which is recessed at intervals along its longitudinal edge and then split longitudinally at intervals, such split portions communicating with the recesses and thus providing a plurality of companion lugs L and L' throughout the length of the guard rails. The lugs L and L' are arranged in pairs, with the lugs of each pair being bent downwardly at right angles and in opposite directions so as to embrace the opposite sides of the corresponding tie. In

the applied position of each of the guard rails D, each pair of lugs L and L' engages a tie T, the guard rail being secured as a unit upon the tie and to the corresponding girder by means of hooked end bolts B. The upper or threaded end of each bolt B carries a nut 15 which, during the application of the bolt, is removed and applied after the bolt shank has been passed through a tie. 65 As shown in Figs. 1 and 2, a bolt B is provided at alternate ties, the bolt extending through the bottom web of the guard rail and through the corresponding tie T its hooked end engaging the under side of the 70 upper flanged edge of the girder G and securely locked in such position by a vertical adjustment of the bolt through the medium of the nut 15. With both of the guard rails secured in this manner, it will be clear that 75 relative movement of the guard rails with respect to the ties is prevented while the guard rails and ties are securely held to the girders G against movement in any direction. The lugs L by embracing the opposite sides of 80 the tie provide further means for securing the ties in spaced relation at all times so as to provide an efficient support for the rails R of the railway track.

It is to be particularly noted that because 85 of the construction of the guard rails and the manner in which they are applied to the ties and girders that they can be readily removed from the same when it is necessary to substitute new ties, for those which 90 have become worn and useless, without in any way distorting the guard rail so that they can be re-applied to the ties when functioning in the same successful manner.

Although I have herein shown and described only one form of guard rail and only one means for securing the rails and girders to a railway bridge, it is to be understood that various changes and modifications may be made herein without departing from the 105 spirit of the invention and the spirit and scope of the appended claims.

What I claim is:

1. A guard rail comprising, a bar recessed at intervals along one longitudinal edge and split longitudinally at intervals to provide lugs, said lugs being bent at right angles in the plane of the bar and arranged in pairs, with the lugs of each pair spaced apart to accommodate a railway tie and to embrace the opposite sides of the same. 110

2. A guard rail comprising, an angle bar

having one web thereof formed with right angularly disposed lugs, said lugs being arranged in pairs with the lugs of each pair spaced apart to accommodate a railway tie and to embrace the opposite sides thereof.

3. A railway bridge comprising, in combination, girders, ties arranged at intervals and extending transversely of the girders, rails supported on said ties, guard rails on

said ties, each of said guard rails comprising 10 a bar formed with depending lugs, said lugs being arranged in pairs with the lugs of each pair embracing the opposite sides of one of the railway ties, and hooked end bolts 15 extending through said bars and ties and having the hooked ends thereof engaging said girders.

WILLARD HARRISON ELLIS.
